UNITED STATES PATENT OFFICE.

RICHARD CALDWELL, OF TIPTON, MICHIGAN.

WAGON-RACK.

SPECIFICATION forming part of Letters Patent No. 380,181, dated March 27, 1888.

Application filed November 7, 1887. Serial No. 254,501. (No model.)

To all whom it may concern:

Be it known that I, RICHARD CALDWELL, a citizen of the United States, residing at Tipton, in the county of Lenawee and State of Michigan, have invented certain new and useful Improvements in Wagon-Racks, of which the following is a specification, reference being had therein to the accompanying drawings.

This invention relates to new and useful improvements in combination-racks for wagons; and the invention consists in the peculiar construction and arrangement of the parts, whereby great strength may be secured with close economy in construction, and which may be readily secured to or removed from the wagon-box, and may be adjusted for use as a hay-rack or a cattle-rack, as occasion requires, all as more fully hereinafter set forth.

In the drawings which accompany this specification, Figure 1 is a perspective view of my improved rack attached to an ordinary wagon-box and adjusted as a hay-rack. Fig. 2 is a perspective view of the same adjusted for use as a cattle-rack. Fig. 3 is a cross-section 25 through a pair of the stakes of the rack, and Fig. 4 is a detached perspective of one of the caps. Fig. 5 is a longitudinal section.

A are the sides, B the ends, C the flooring, and F the cross-girts, of a wagon-box of ordinary construction. The ends of the girts project from the sides of the wagon-box, and are provided with mortises *a*, which form keepers in which the lower ends of the stakes *G* of the side racks, *D*, engage. These stakes consist of 35 two parts hinged together. The lower part, *G'*, is of greater height than the wagon-box, and the upper part, *I*, is of suitable length to attach thereto the longitudinal strips *J* which form the rack. The hinge-connection between 40 the two parts of the stakes is preferably constructed in the form of a rule-joint, with a metallic tongue, *c*, secured in the upper part and entering into a slot in the lower part, and connected thereto by means of the hinge-pin *d*.

45 The top of the stake *G* is provided with the inward projection *e*, which rests upon the top of the wagon-box, and with the downwardly-projecting flange *f*, which holds the stake securely in place on the wagon-box. I prefer- 50 ably make the lip-flange *f* integrally in one piece with the metallic cap *k*, as shown in Fig.

4. This cap is merely intended to re-enforce the top of the stake *G* to prevent all danger of the wood splitting. It will thus be readily understood that the lower part of the stake is 55 held firmly in position on the side of the wagon-box, while the upper part freely turns outward upon the joint.

To support the racks in an inclined position for use as a hay-rack, as shown in Fig. 1, each 60 stake is provided with a brace, or preferably a pair of braces, *h h*, which turn on a fixed pivot, *i*, on the upper part of the stake, and are connected together at the lower end by means of a pin, *j*, which engages into a slot, *l*, 65 in the lower part of the stake, to allow of a vertical movement of the pin *j* in changing the position of the racks. Instead of the pin *j*, one or more of the braces may be provided with a bolt and thumb-nut, *k*, by means of 70 which the two braces may be firmly clamped against the sides of the stakes, and the rack thus be held in its adjusted position against accidental displacement.

L and M are the end pieces or ladders for 75 the front and rear ends of the wagon-box, respectively, when used for a hay-rack. To secure these ladders in position I secure upon the outside of the end-gates of the wagon-box the wedge-shaped cleats *M*, between which the 80 wedge-shaped lower ends of the ladders are inserted and held in place by the straps *n*, and, if desired, locking-pins *o* may be used to prevent their withdrawal. Thus a secure fastening is had for the ladders, which may be left 85 permanently upon the wagon-box without detracting from its appearance, and also without taking up any space inside the box.

When the rack is in the position shown in Fig. 1, for use as a hay-rack, and it is desired 90 to change it into a cattle-rack, the end ladders are removed and the side stakes are straightened up into a vertical position. In place of the ladders, I then secure the end racks, *N N'*, which are shown in Fig. 2, and are formed of 95 the uprights *p* and the cross-strips *r*, and which are secured in position by means of locking-bolts *s*, which pass through the side racks and the end racks. The uprights *p* extend down inside the wagon-box, and at their lower 100 points are provided with a pin, *t*, which engages into a suitable recess formed in the inner

face of the end-gate to prevent the cattle, sheep, or hogs confined inside from lifting the rack up out of its position on the box, and thereby finding an avenue of escape.

5 To change from the cattle-rack into a hay-rack, the locking-bolts and end racks are removed from their position, the side racks turned outwardly, and the end ladders put in place, all of which takes but little time and 10 labor. In this connection it will be noticed that the ends of the braces *h* rest upon the girts *F*, so that the weight which they sustain is brought onto the latter instead of on the pin *i*. It will thus be seen that the only parts 15 which are required to be changed in adjusting the rack from one use to another are the end pieces and locking-bolts or tie-rods. There are no loose parts, as in other constructions, and no extra supports are required to be put 20 upon the wagon-box to hold the rack in position. Any ordinary wagon-box may be provided with my attachment, and in the absence of the girts *F* suitable keepers to set the stakes in may be provided of iron and attached to 25 the under side of the wagon with little expense and without detracting from its appearance.

What I claim as my invention is—

1. In a wagon-rack, the combination, with 30 the wagon-body, of the side racks, *D*, consisting of the stakes *G*, constructed in two parts hinged together, the upper part having the longitudinal strips *J* secured to it and the lower part engaging into keepers on the wagon-box, 35 and provided with the elongated slot *t* and the projection *e* and the overhanging flange *f*, and the parallel braces *h*, pivotally secured at their upper ends and connected at their lower ends with a pin or bolt engaging into the slot 40 in the lower part of the stake, all substantially as described.

2. In a wagon-rack, the combination, with

the wagon-body, of the side racks, *D*, consisting of the stakes *G*, constructed in two parts 45 hinged together, the upper part having the longitudinal strips *J* secured to it and the lower part engaging into keepers on the wagon-box, and provided with the projection *e* and the metallic cap *k*, covering the top of the stake and forming a part of the hinge, and having the overhanging flange *f*, and the braces *h*, pivotally secured at their upper ends and connected at their lower ends by a pin or bolt 50 engaging into a slot in the lower part of the stake, all substantially as described. 55

3. In a wagon-rack, the wagon-body, the side racks, *D*, the end racks, *L M*, supported upon the end-gates of the wagon and engaging therewith against vertical displacement, the wedge-shaped cleats *m*, the straps *n*, the locking-bolt *o*, passed through the strap into the end rack, and the locking-bolts *s*, all combined to operate substantially as described. 60

4. In a wagon-rack, the wagon-body, the side racks, *D*, removably secured to the wagon-body, the end racks, *L M*, supported upon the end-gates of the wagon, and having the pins *t*, engaging into said end-gates, and the locking-bolts *s*, passing through the side racks and 65 end racks, substantially as described. 70

5. The combination, with the end-board *B* of the wagon-body, the wedge-shaped cleats *m*, secured to the outside of the end-board and provided with stops *n*, of the ladder *M*, provided with wedge-shaped lower ends, and the locking-bolts *o*, all arranged substantially as 75 described. 75

In testimony whereof I affix my signature, in presence of two witnesses, this 5th day of October, 1887.

RICHARD CALDWELL.
